WEB ROLL SUPPORT

Albert J. Horton, White Plains, N. Y., assignor, by
mesne assignments, to R. Hoe & Co., Inc., New
York, N. Y., a corporation of New York

Application December 29, 1934, Serial No. 759,639

12 Claims. (CL 242—76)

This invention relates to a structure for supporting web rolls and more particularly to a support for a rotatable reel for use in supporting a plurality of web rolls from which webs are fed successively to a printing machine.

The principal object of the invention is to provide an improved means for regulating axial or endwise adjustment of the reel as required to obtain the desired marginal alignment as the 10 web passes through the printing machine.

It is also an object to provide a mechanism for both rotating the roll supporting reel and adjusting the axial position of same which is of generally improved construction, whereby the 15 device will be simple, durable and inexpensive in construction, as well as convenient, practical, serviceable and efficient in use.

With the foregoing and other objects in view which will appear as the description proceeds, 20 the invention resides in the combination and arrangement of parts, and in the details of construction hereinafter described.

The preferred embodiment of the invention is 25 illustrated in the accompanying drawings, wherein:

Figure 1 is an end elevation with parts broken away, and parts in section, showing a reel support and driving mechanism for rotating said reel and also for providing an axial adjustment 30 thereof; and

Figure 2 is a part elevational and part sectional view taken in the direction of the arrow on line 2—2 of Figure 1.

Two roll supporting spiders 10—10, which 35 comprise the reel structure, are shown mounted on a horizontally disposed shaft 11, each spider being provided with a plurality of arms which are adapted to support a plurality of web rolls in the manner shown in Figure 1. The ends of said 40 shaft 11, which extend beyond each end of the reel, are supported by brackets 12 and 13, and the brackets are preferably mounted on the machine frame 14. A bushing 15 freely mounted on the driving end of the shaft 11, is splined as 45 at 20, within a bearing block 16, provided on the bracket 12, and is thereby permitted to be moved axially within the bearing while the shaft 11 is rotated therein. A gear 17 is secured to the driving end of the shaft 11, as shown in Figure 50 2, and abuts one end of the bushing 15. Said gear is preferably driven through a reduction gear drive, which includes a motor driven worm and worm gear 18 and 19 respectively, and a 55 pinion 21 mounted on a worm gear supporting

shaft 22. A bracket 23, secured to the frame 14, has a bearing portion 24, within which one end of the shaft 22 is rotatably mounted. It is to be noted that the width of the pinion 21 is greater than the width of the gear 17 to provide constant mesh of the pinion and gear teeth when the gear position is adjusted, as will be hereinafter explained.

The opposite end of the reel supporting shaft 11 has a sleeve 25 mounted thereon, and said sleeve is mounted in a bearing block 26, provided on the bracket 13, in a manner which will permit the sleeve to move axially but not rotatively while the shaft is permitted to rotate within the sleeve. To provide for these conditions, the sleeve 25 is maintained in a fixed axial relation with the shaft by means of an annular internal flange 28 at the outer end of the sleeve which is confined between a shoulder 27 on the shaft and a collar 31 secured to the end of the shaft. A projection or lug 32 extends radially outward from the sleeve 25 at the central portion thereof and has a screw threaded opening 33 therein. A shaft 34 rotatably mounted in bearings 35 in the bearing block 26, has a screw 36 thereon which engages the screw thread of the opening 33, and thus provides a means for holding the sleeve against rotation when the reel supporting shaft is rotated.

To move the sleeve endwise within the bearing block, the screw shaft 34 is rotated. This causes the screw 36 to rotate within the threaded opening 33 of the projection 32 and thus move the sleeve forward or backward. The said screw shaft may be rotated in any desired manner but is preferably power driven through a reduction drive including a worm and worm gear shown at 37 and 38 respectively. The worm gear 38 is secured to the screw shaft 34, while the worm 37 has shaft extensions 39—39 rotatably mounted in bearings 41—41, the latter being mounted in a housing 42 secured to the bracket 13. A motor 43, supported on the frame 14, is connected in a driving relation with the shaft 39.

The driving mechanism, which is provided to rotate the roll supporting reel, is arranged in a simple and effective manner at one end of the reel supporting shaft 11, whereas the mechanism provided to adjust the reel in an endwise or axial direction for obtaining marginal alignment, is located at the opposite end of the shaft 11, each mechanism being arranged in a manner which offers the least resistance to co-operative operation between the two movements.

The drive of the sleeve 25 by the rotation of the screw 36 provides for a simple axial adjustment of the shaft 11, and the arrangement of the gear 17 to slide along the teeth of the pinion 21, 5 while remaining in full contact therewith due to the greater length of said pinion teeth, thus provides simple and effective rotational movement.

Means is also provided to limit the endwise movement of the shaft 11, which includes two 10 limit switches 46, 47, each having an operating arm 44 and 45 connected therewith and positioned at either side of a finger 46 secured to the bushing 15, said finger being adapted to engage and rock either of the arms 44 or 45 to open a 15 switch 46 or 47 and thereby break a circuit to the motor 43 when a predetermined limit of movement of said shaft 11 has been reached.

It will be understood that the invention may be embodied in other specific forms without departing from the spirit or essential attributes thereof, and it is therefore desired that the present embodiment be considered in all respects as illustrative and not restrictive, reference being had to the claims rather than to the foregoing 25 description to indicate the scope of the invention.

What I claim is:

1. In a web roll support, the combination of a roll supporting reel having a shaft, means to support said shaft at each end thereof and means 30 to rotate same, means to adjust said shaft including a sleeve confined to one end of the shaft and axially movable within the support, a screw in operative engagement with said sleeve to move same coaxially with the shaft and thereby adjust 35 the axial position of the reel, and means to rotate said screw.

2. In a web roll support, the combination of a roll supporting reel, a reel supporting shaft, a sleeve at one end of the shaft and held against 40 axial movement thereon, a bearing block arranged to support the sleeve while permitting axial but not rotary movement thereof, a projection on said sleeve and having a screw thread formed therein, a screw rotatably supported in 45 the bearing block and engaging said screw thread, and a power drive for rotating the screw to thereby adjust the axial position of the reel.

3. In a web roll support, the combination of a roll supporting reel, a reel supporting shaft, a 50 sleeve at one end of the shaft and held against axial movement thereon, a bearing block arranged to support the sleeve while permitting axial but not rotary movement thereof, a projection on said sleeve and having a screw thread 55 formed therein, a screw rotatably supported in the bearing block and engaging said screw thread, and a power drive for rotating the screw to thereby adjust the axial position of the reel, a finger extending from said reel supporting shaft and limit 60 switches electrically connected with the power drive, each having an actuating arm extending in the path of said finger, whereby the power drive circuit may be broken after a predetermined distance of movement of the shaft in 65 either axial direction.

4. In a web roll support, the combination of a roll supporting reel, a reel supporting shaft, a sleeve at one end of the shaft and held against 70 axial movement thereon, a bearing block arranged to support the sleeve while permitting axial but not rotary movement thereof, a screw associated with said sleeve and adapted to adjust the axial position of the sleeve, and means to rotate said screw to thereby adjust the axial 75 position of the reel, a gear on the opposite end

of the reel supporting shaft and axially movable therewith, a pinion having teeth along which the teeth of the gear are arranged to move and maintain full running contact while permitting extreme shaft adjustments to be made, and means 5 to drive said pinion.

5. In a roll supporting reel having a shaft, sleeve members in which said shaft is rotatably supported adjacent each end, means to confine one end of the shaft to one sleeve, supports in 10 which said sleeves are axially movable, means for moving the confined sleeve axially to thereby move the shaft, and means for rotating the shaft.

6. In a web roll supporting reel having a shaft, a bearing member at each end of said shaft, 15 said shaft being rotatable and confined against axial movement in both of said members, a support for each member and in which they are axially slidable, and means engaging one of said members to axially move both of said members 20 whereby said shaft and reel are axially moved.

7. In a web roll supporting reel having a shaft, a bearing member at each end of said shaft, said shaft being rotatable and confined against axial movement in both of said members, a support 25 for each member and in which they are axially slidable, means engaging one of said members to axially move said shaft and reel, and means associated with one of said members to control said moving means to limit the extent of the 30 aforesaid axial movement.

8. In a web roll supporting reel having a shaft, a bearing member at each end of said shaft, said shaft being rotatable in said members and confined against axial movement in one, a support 35 for each member and in which said members are axially slidable, means to axially move the member in which said shaft is confined whereby said shaft and reel are axially moved, and means to rotate said shaft including a gear secured thereto 40 and axially movable therewith, and another gear in mesh with the first mentioned gear, one of said gears being wider than the other whereby full running contact is assured in all adjusted 45 positions of said reel.

9. In a web roll supporting reel having a shaft, a bearing member at each end of said shaft, said shaft being rotatable and confined against axial movement in both of said members, a support 50 for each member and in which they are axially slidable, means to axially move said shaft and one of said members, and means on said moved member to control said moving means to limit the extent of such movement.

10. In a web roll supporting reel having a 55 shaft, a bearing member at each end of said shaft, said shaft being rotatable and confined against axial movement in both of said members, a support for each member and in which they are axially slidable, means engaging one of said members to axially move said shaft and reel, and means movable with said shaft to control 60 said member moving means to limit the extent of the movement of said shaft in both directions.

11. In a web roll supporting reel, a shaft upon 65 which the reel is supported, a bearing block at each end of the shaft and concentric therewith relatively to which the shaft is axially slidable, the bearing block at one end of the shaft supporting a sleeve in which the shaft is rotatable, 70 the sleeve being connected to the shaft for axial movement therewith, means to rotate said shaft, means acting through said sleeve to axially move said shaft, and means movable axially with the 75 shaft and controlling the means to axially move

the shaft, to limit the extent of such movement.

12. In a web roll supporting reel, a shaft upon which the reel is supported, a bearing block at each end of the shaft and concentric therewith relatively to which the shaft is axially slideable, the bearing block at one end of the shaft supporting a sleeve in which the shaft is rotatable, means to connect the sleeve to the shaft to prevent relative axial movement therebetween, a lat-

eral extension on the sleeve, means to engage said extension to move said sleeve and with it said shaft axially in said bearings, an electric motor to actuate said sleeve moving means, a control for said motor, and means movable axially with said shaft to actuate said control and limit the extent of the axial movement of said shaft. 5

ALBERT J. HORTON.
